United States Patent

Des. 235,362
Patented June 10, 1975

235,362

EXERCISER

Richard H. Pray, 5156 Via Valverde,
Santa Barbara, Calif. 93111

Filed Dec. 19, 1973, Ser. No. 426,303

Term of patent 14 years

Int. Cl. D21—02

U.S. CL. D34—5 K

Fig. 3

Fig. 1

Fig. 2

FIG. 1 is a front perspective view of an exerciser showing my new design;

FIG. 2 is a side elevational view thereof; and

FIG. 3 is a top plan view thereof with portions of the rope omitted for convenience of illustration.

I claim:

The ornamental design for an exerciser, as shown and described.
